(57) **CLAIM**

The ornamental design for a microphone stand, as shown and described.

DESCRIPTION

FIG. 1 is a front perspective view of a microphone stand; FIG. 2 is a rear perspective view of the microphone stand; FIG. 3 is a front elevational view of the microphone stand; FIG. 4 is a rear elevational view of the microphone stand; FIG. 5 is a top plan view of the microphone stand; FIG. 6 is a bottom plan view of the microphone stand; FIG. 7 is a right side elevational view of the microphone stand; FIG. 8 is a left side elevational view of the microphone stand; and,

FIG. 9 is a sectional view of the microphone stand taken along line 9-9 of FIG. 5, wherein FIG. 9 illustrates a profile in the two-dimensional plane of the cross-section and omits illustration of anything internal system in the microphone stand and outside the two-dimensional plane.

The broken lines depict environment that forms no part of the claimed design.
